APPARATUS FOR THE SPECIFIC GRAVITY
CLASSIFICATION OF BULK SUBSTANCES

Walter Vogel, Santiago, Chile

Application July 23, 1947, Serial No. 763,121
In Switzerland September 11, 1946

6 Claims. (Cl. 209—422)

1

The present invention relates to apparatus for the specific gravity classification of bulk substances, utilizing finely granulated separating media. Such separating media may be sand, gravel or other material reduced to suitable size, in conjunction with apparatus adequate for carrying the process into effect.

More specifically the invention relates to apparatus for specific gravity classification of bulk substances in which the finely granulated media and the material to be separated flow in strata in an inclined stream greater than the natural angle of repose of the media and including means for discharging the media after first changing the direction of flow thereof at different relative velocities.

German Patent 740,005 discloses a process for accomplishing separation in a stream of a finely granulated separating medium advancing in an adequate trough with the velocity of the diverse layers thereof increasing from the lower to the upper layers. In such case the stream of separating medium conducts itself as if it were a liquid in which, in accordance with the Archimedean principle, the heavier particles gradually sink to the bottom of the separating medium and the lighter particles are carried to the top. In this known process the diverse velocities of the advance movement of the finely granulated separating medium is achieved by expedient election of the angle of the slope of the trough in the interior of which the separating process is accomplished, as well as by adjustment of a blade for dividing the stream of separating medium, located at the discharge end of the trough. Experiments have shown that in this manner it is not possible to accomplish satisfactory separation because of the fact that the diverse velocities, upon which principle this separating process is based, do not remain constant throughout the separating medium until it reaches the discharge end.

Therefore, the present invention has for an object the elimination of these difficulties and the provision of structure that permits adequate separation, the intensity of which can be regulated at will inasmuch as adequate provision has been made to insure discharge of the diverse layers of the separating medium at diverse velocities.

In one form of preferential execution of this invention, separation is accomplished in a covered trough, sloping downwardly at an angle slightly greater than the natural angle of repose, the desired effect can be achieved by discharging the separating media from the trough over one or more movable surfaces placed at an adequate angle in relation to the advance movement thereof. The velocity of these surfaces differs in

2

the various sections where the diverse layers of separating medium impinge upon same.

The specific gravity classification of more than two substances can very conveniently be accomplished by means of this invention and for this purpose two or more superimposed layers of separating media diminishing in specific gravity from the bottom to the top, are used simultaneously. If for example it is desired to obtain three products, two finely granulated separating media of diverse specific gravity are used, that is, an upper layer of lesser specific gravity over a lower layer of greater specific gravity. These layers advance in the trough simultaneously. At the discharge end of the trough the light weight substance will be in the uppermost layer, the middle weight substance will be in the intermediate layer, and the heavy weight substance will be in the lowermost layer, and same may be removed therefrom by screening each layer individually so as to recover the separating media for re-use in the trough aforementioned.

It is advantageous to use separating media having similar angles of repose. In some cases, in order to avoid intermingling of the layers, it may be expedient that the granulations of the separating medium of greater specific gravity be smaller than the granulations of the separating medium of lesser specific gravity. It may also be advantageous to have between the two layers of separating media of diverse specific gravities, an intermediate layer composed of a mixture of the adjoining layers, which mixture generally forms spontaneously during operation of apparatus covered by this invention.

In order to maintain a constant separative intensity, the specific gravities as well as the angles of repose of the granulates of separating media should be maintained without variation. For this purpose the invention may be complemented with means for the continuous elimination of residues accumulating during the separating process, as well as for elimination of the secondary granulations that gradually accumulate in the separating media through screening thereof after the division of the diverse layers, which diminishes the purity thereof as a result of the inclusion of extraneous material.

For greater convenience it is possible to pass through a cleaning device, a partial stream of the separating medium used in any closed circuit. The method used may be, for example, either hydromechanical separation in a decantation machine, or pneumatic cleaning by means of air currents. If the hydromechanical method is used, the cleaned separating medium must be dried before being re-used in the separating process.

Many advantages are derived by using as a

separating medium a material capable of being magnetized, the cleaning of which may subsequently be accomplished by magnetic separation, by merely passing a partial stream of the separating medium over an adequate magnetic field.

The purpose of this invention may also be achieved by using as a separating medium, hollow iron balls, in sizes and wall thicknesses proportionate to the specific gravity desired. It is likewise possible to use cast materials, such as metallic alloys or glass, slag and ceramic materials, such as porcelain or materials held together by means of resins or other binding agents, including ferrous aggregates, in any given size required, and also, if necessary, spherical in structure. The use of such materials is particularly applicable in the separation of large bulk substances, inasmuch as in such cases it is thereby possible to select the most adequate proportion of the size of granulation of the separating media.

Finally, advantages may be derived by selecting as a separating medium a material whose hardness is greater than the hardest residue of the substance to be separated, so that during continuous contact thereof with the substance being separated in the trough, the residue as well as the secondary granulations will continue to disintegrate as a result of friction with the harder separating medium, and can then be separated therefrom by a simple screening operation. For this purpose the size of granulation chosen for the separating medium must be larger than the size of the perforation or mesh of the screen used therefor. For example, in the separation of stock-piled bulk coal, the separating media used may be hollow cast steel or basalt balls, or solid glass balls 8 to 10 mms. in diameter. Thus a 12 mm. mesh screen may be used to recover the substance to be separated, and an 8 mm. mesh screen may be used to recover the separating medium from the residue, and if the screen be combined with a conveyer, it will be possible to return in a continuous manner, the screened separating medium to the principal circuit of the process effected by this invention. The invention will now be described with particular reference to the accompanying drawings in which Figure 1 is a vertical cross sectional view of one form of apparatus utilizing a revolving plate for discharging the layers or strata at different relative velocities, Figure 2 is a horizontal cross sectional view of the arrangement shown in Figure 1, Figure 3 is a vertical cross section of a modified form of the invention, and Figure 4 is a horizontal cross sectional view of the arrangement shown in Figure 3.

Reference will be made to the aforementioned figures in explaining hereinafter the operating principle of the applicable process and the operation of the apparatus shown in the accompanying drawings.

The form of apparatus shown in Figures 1 and 2 comprises a downwardly sloping covered trough 1, at the head or upper end of which there is a double feed hopper including inlet funnels 2 and 3, for receiving the separating media, and, between said funnels, a duct 4, through which the substance to be separated is fed. The discharge end of trough 1, projects over the surface of a revolving plate 5, supported on shaft 6. Concentrically above revolving plate 5 there is a truncated-cone-shaped disk 7, whose surface 1a, slopes along the same plane as the bottom of the trough, and said surface serves to direct the lower layer S1, of the separating media, from 75

the trough to the aforementioned revolving plate.

Looking in the direction of rotation of the revolving plate 5, the front wall 1a of trough 1, has a discharge opening 8, leading to said revolving plate. As a result of the rotation of revolving plate 5, the separating medium leaves the trough laterally at a velocity which increases from the rim of disk 7 to the perimeter of revolving plate 5. Above revolving plate 5 there are two stationary dividing blades 9 and 9a, which slope at an angle corresponding to the angle of repose of the substance to be separated. One of the dividing blades 9, commences slightly beyond the lateral discharge opening 8, of the trough, and separates the exterior layer S1, containing the light weight substance, from layer S2, containing the heavy weight substance. Exterior layer S1, is gradually advanced by and along dividing blade 9, to the perimeter of revolving plate 5, and then drops into a collection receptacle, not shown. Interior layer S2, containing the heavy weight substance, rotates with revolving plate 5, and is likewise gradually advanced by and along dividing blade 9a, to the perimeter of revolving plate 5, until it drops off. Revolving plate 5 is driven by any conventional means and rotates at such a velocity that the advance movement of the separating medium in the trough is not obstructed.

The modified form of execution of the apparatus hereinbefore described, of which Figure 3 is a vertical cross section and Figure 4 is a horizontal cross section, differs from the preceding form of execution only in that a truncated-cone-shaped disk 10, is mounted above revolving plate 5, not concentrically but rather eccentrically, in relation to the supporting shaft 6, of said revolving plate 5. The diameter of disk 10, is such that one side of its surface projects beyond the edge of revolving plate 5. Disk 10 rests upon revolving plate 5 and may be rotated either around shaft 11, on which shaft 11 may be a propelling shaft, and conventional driving means which are not shown are utilized. This disk may also be propelled by revolving disk 5. Due to the eccentricity of disk 10, it serves simultaneously to divide the separating medium and to maintain the diverse layers thereof. Layers S1 and S2 are dropped one after the other from the perimeter of revolving plate 5. The light weight products S1, will be the first to drop off, and subsequently the heavy weight products, S2, will gradually drop off. Separation of each of the products dropped from the revolving plate is accomplished by means of adjustable blades denoted diagrammatically at 12 or other similar devices accomplishing this result. Inasmuch as in this case there are no dividing blades on revolving plate 5, which the separating medium advances, it is impossible for the separating medium to choke before leaving the trough. Shafts 6 and 11, and hence, revolving plate 5 and disk 10, may also be used in an inclined position. In both forms of execution hereinbefore described, both the bottom of trough 1, and the side wall facing the direction of rotation terminate approximately on the same plane as the upper surface of the disks 7 or 10, respectively. In addition, the opposite side wall extends downwardly and terminates immediately superjacent the surface of the plate 5 and the top wall of the trough likewise extends down and terminates in the same plane as the opposite side walls. Thus, the materials and media flowing down the covered trough can only discharge laterally of the trough due to the rotation of plate 5.

It is therefore clear that I have provided an apparatus including the covered trough 1 sloped at an angle slightly greater than the natural angle of repose of the masses of separating media, which as indicated previously are finely granulated material such as sand, gravel and the like. At the head or upper end of the trough are plural feed means communicating with the trough comprising funnels or hoppers 2 and 3 respectively receiving and discharging into the trough finely granulated separating media of different specific gravities and a duct or pipe 4 into which is fed the material to be classified, such as bulk coal. The trough of course, due to its 10 inclination and length, is such that in the dry stream flowing therethrough stratification will occur in such fashion that the light weight constituents of the masses will be at the top of the stream, the heavy weight constituents will be at the bottom and the intermediate layer or strata will comprise the substance of intermediate specific gravities. The bottom of the trough extends down to and terminates approximately in the plane of the upper surface of the truncated cone-shaped disk 7 or 10, as the case may be, the top of the trough extends down and terminates immediately above the revolving plate 5 beneath the disk 7 or 10. The side wall of the trough facing the direction of rotation is broken away and terminates with the lower edge substantially in the plane of the upper surface of the disk 7 or 10. Thus, the strata flowing down the trough at an angle meet the revolving plate which is shown disposed horizontally and has its direction changed. The revolving plate continues the advance or feed of the material from the trough and conveys it laterally away from the trough. Inasmuch as the velocity of portions of the plate increase from its axis outward to its perimeter the different strata, particularly the lighter strata at the top of the trough and the heavy strata at the bottom, will impinge upon the plate at portions traveling at different relative velocities. It is noted that the slope of the disks is approximately the same angle as the slope in the bottom of the trough. Thus, the rotation of the plate will impart movement to the strata such that the light weight material will tend to move radially and advance toward the perimeter of the plate. In Figures 1 and 2 the stationary blades 9 and 9a, which as shown are inclined at approximately the same angle as the angle of the trough, divide the stream so that the light weight materials S1 move along the blade 9 to the perimeter of the plate where they drop off. As indicated, this strata or layer comprises light weight particles of the material to be separated and also portions of separating media such as sand. Obviously the flow from the plate can be screened whereby the separating media is removed from the material such as coal and returned back to the feed end of the trough for reintroduction into the hoppers 2 and 3. Likewise, the return flow of separating media can be screened so that the specific gravities of the particles of media reintroduced into the hoppers 2 and 3 are the same as the original charge of medium. As shown in Figure 2, the heavy weight particles are carried by the plate and disk until they reach the blade 9a which causes them to move outwardly toward the perimeter of the plate for removal therefrom.

In Figure 3 the stationary blades 9 are eliminated by mounting the disk 10 eccentrically of the axis of the plate 5. Thus, the strata dis-

charged from the trough 1 flowing laterally thereof due to the rotation of the plate reach the perimeter of the disk over a wider area than the initial area at the base of the trough. The light weight substances S1 initially reaching the plate farther away from the axis than the heavy weight substances S2 will naturally reach the perimeter of the plate in spaced relation to the heavy weight substances which tend to follow the surface of the disk. Thus, the blades 12 which are adjustable can divide the stream passing over the edge of the plate in the different strata of different specific gravities. Here again the removed strata can be screened so that the separating medium is separated from the coal on the one hand and slate or rock on the other, and which medium can be further screened and reintroduced into the hoppers 2 and 3.

Thus, it is clear that in both forms of the invention I have provided in combination with a closed inclined trough sloped at an angle greater than the natural angle of repose of the separating medium a rotatable plate disposed at an angle to the axis of the trough and a disk above the plate having a conical surface sloping at substantially the same angle as the angle of slope of the trough and which trough has a discharge opening facing the direction of rotation, the stream of material and the medium stratifying during its flow through the trough and hitting plate portions having relative velocities, the plate and disk thus constituting conveying means at the lower end of the trough which continue the flow of the stream in an arcuate path and carry the strata of the stream at different relative velocities corresponding to the radius of the circle of the path they respectively travel, and means for removing the different strata which comprise the stationary blades 9 and 9a on the one hand and the combination of the eccentricity of the disk 10 and the adjustable blades 12 on the other.

Therefore, what I claim as my invention is:

1. In an apparatus for separating materials according to specific gravities, the combination of an inclined trough having upper and lower ends, said trough confining a flowing stream of finely granulated stratified separating medium and material to be separated therein and said trough being at least slightly more inclined than the natural angle of repose of said medium so that the mass of medium and materials flows downwardly, means at the upper end of the trough for feeding the materials to be separated and the medium to the trough, rotatable conveying means at the lower end of the trough rotating in such direction as to continue the flow of said stream in an arcuate path, said conveying means receiving and carrying strata of said stream at different velocities corresponding to the radius of the circle they have to follow, said conveying means comprising a rotatable plate and a truncated cone-shaped member mounted above the plate having its conical surface sloping in the plane of the bottom of the trough, and means mounting said member for movement eccentrically of the plate for pushing the strata and materials therein discharged from the trough to the perimeter of the plate for separate removal.

2. In an apparatus for specific gravity classification of bulk substances the combination of an inclined trough including top, bottom and opposite side walls and terminating in upper and lower ends, means at the upper end of the trough

for separately feeding finely granulated dry separating medium and substances to be classified to the trough, said trough sloping at an angle at least slightly greater than the natural angle of repose of the said medium so that the medium and substances flow downwardly through the trough and stratify therein with the light weight substances moving in the top of the stream and the heavy weight substances in the bottom, rotatable conveying means at the lower end of the trough comprising a rotatable plate member disposed at an angle to the axis of the trough and a truncated cone-shaped member mounted above the plate member and having its conical surface at substantially the same angle as and sloping in the plane of the bottom of the trough, the bottom of said trough terminating approximately at the upper surface of said cone-shaped member, the side wall of said trough facing the direction of rotation of said plate terminating in spaced relation to said plate to provide a lateral discharge opening and the top and opposite side walls of said trough projecting beyond said first mentioned side wall and terminating immediately adjacent the surface of said plate whereby different strata of substances and medium impinge upon the plate at different distances from the center thereof, thus upon portions having different relative velocities, and the plate carrying said strata laterally of said trough at different velocities corresponding to the radius of the circle the different weight strata follow, and the strata being removed from the plate at different portions of its perimeter.

3. In an apparatus as defined in and by claim 2, in which stationary blades project over said plate so that the different strata are removed therealong, said blades being inclined at substantially the same angle as the angle of slope of said trough.

4. In an apparatus for separating materials according to specific gravities, the combination of an inclined trough; means for feeding to the upper end of said trough a mass of a finely granulated separating medium to form a lower stratum in said trough; means for feeding to the upper end of said trough a mass of a finely granulated separating medium to form an upper stratum in said trough; means for feeding to the upper end of said trough the materials to be separated intermediate said lower and upper strata, the inclination of said trough being sufficiently greater than the natural angle of repose of said masses to cause said masses and said materials to flow downwardly through said trough; means for discharging said strata and the separated materials therein from the lower end of said trough at different relative velocities, comprising a rotatable member adjacent the discharge end of said trough and having two surfaces moving at different relative velocities, respectively, when said member is rotated, means for discharging said strata and the separated materials therein from said trough to said surfaces, respectively, and means for removing the discharged strata and materials from said surfaces.

5. In an apparatus for separating materials according to specific gravities, the combination of an inclined trough; means for feeding to the upper end of said trough a mass of a finely granulated separating medium to form a lower stratum in said trough; means for feeding to the upper

end of said trough a mass of a finely granulated separating medium to form an upper stratum in said trough; means for feeding to the upper end of said trough the materials to be separated intermediate said lower and upper strata, the inclination of said trough being sufficiently greater than the natural angle of repose of said masses to cause said masses and said materials to flow downwardly through said trough; means for discharging said strata and the separated materials therein from the lower end of said trough at different relative velocities, comprising a rotating plate adjacent the discharge end of said trough, means for discharging said strata and the separated materials therein from said trough onto areas of said plate at different distances from the axis of rotation of said plate, respectively, and means for removing the discharged strata and materials therein from said plate, separately.

6. In an apparatus for separating materials according to specific gravities, the combination of an inclined trough; means for feeding to the upper end of said trough a mass of a finely granulated separating medium to form a lower stratum in said trough; means for feeding to the upper end of said trough the materials to be separated intermediate said lower and upper strata, the inclination of said trough being sufficiently greater than the natural angle of repose of said masses to cause said masses and said materials to flow downwardly through said trough; means for discharging said strata and the separated materials therein from the lower end of said trough at different relative velocities including a rotating plate adjacent the discharge end of the said trough, a truncated-cone-shaped disk mounted on said plate, whose surface slopes in the plane of the bottom of said trough, means for discharging said strata and the separated materials therein from said trough onto areas of said plate at different distances from the axis of rotation of said plate, respectively, and means for removing the discharged strata and materials therein from said plate, separately.
